UNITED STATES PATENT OFFICE.

JOSEPH DE BRACHT, OF ALTOONA, PENNSYLVANIA, ASSIGNOR OF ONE-HALF TO PAUL EPRIGHT, OF ALTOONA, PENNSYLVANIA.

INDICATOR OR PROMPTER FOR HOUSEHOLD OR OTHER PURPOSES.

Application filed January 10, 1928. Serial No. 245,768.

This invention relates to a device to be used as a reminder or prompter to indicate household articles to be purchased, dates to be kept, persons to be interviewed, or other 5 indicia, to which attention is desired to be called.

A primary object of the invention is to provide a device of this character, which will disclose at a glance the matter to be 10 called to attention, and which is so marked and displayed, that it will stand out prominently and attract the attention of the party for whom it is intended.

Another object is to so construct a device 15 of this character which, when the matter to which attention is called has been taken care of, may have the attention attracting indicia replaced in the negative column out of prominence and where it normally re- 20 mains.

This invention, also, while primarily intended for the purposes above set forth, may be used for advertising purposes in stores, restaurants, and the like, it is so 25 constructed that the indicia to be displayed may be readily changed at will.

In carrying out these objects, the invention is susceptible of modification without departing from the spirit or sacrificing any 30 of the advantages of the claimed invention; there being shown in the drawings for illustrative purposes a preferred and practical form, in which;

Figure 1 represents a front elevation with 35 parts broken out, of a device constructed in accordance with this invention.

Fig. 2 is a detail transverse section there- 40 of showing the mounting of one of the slides used in connection with the indicator,

Fig. 3 is a section taken on the line 3—3 of Fig. 1, it being a transverse section at 45 the point indicated,

Fig. 4 is a detail longitudinal section taken on the line 4—4 of Fig. 1,

Fig. 5 is a transverse section taken on the line 5—5 of Fig. 1.

Fig. 5^a is a front elevation showing a slightly different form of the invention,

Fig. 6 is a longitudinal section taken on 50 the line 6—6 of Fig. 5^a,

Fig. 7 is a transverse section taken on the line 7—7 of Fig. 5^a, and

Fig. 8 is a detail perspective view of one of the slides used in the form illustrated in Fig. 5^a.

In the embodiment illustrated in Figs. 1 to 5, the indicator constituting this invention comprises a base plate 1 which may be constructed of any suitable material, and of any desired size, and which is shown provided with a frame or reinforced side members 2 which are preferably made removable, for a purpose presently to be described.

This base plate 1 is shown provided at 65 its upper end with apertures 3 to provide for its suspension from a suitable support, and adjacent said apertures is arranged a blank space or plate 4 to contain instructions, advertising matter, or other indicia. 70

At the lower end of the base plate 1 is shown mounted a scratch pad 5 for use in writing down articles needed, which are not indicated on the slides of the reminder. This pad 5 is shown mounted in guides 6 75 extending longitudinally of the base plate and spaced transversely from each other, as shown clearly in Figs. 1 and 3, while arranged below the plane of these guides is a rest 7 to support the lower edge of the 80 pad 5, and from the front edge of which extends concavo-convex rests 8 to receive and support a pencil, indicated in dotted lines at P.

The base plate 1 is provided with a plurality of transversely extending guides 10 arranged to alternate with each other, as shown clearly in Fig. 1, one of said guides extending from one side edge of the base plate to a point beyond the mid-center 90 thereof in one direction, while the adjacent guide extends from the other side edge in the opposite direction to a point beyond the mid-center of the plate. These guides 10 are provided by slitting the base plate 1 transversely, the slits 11 being spaced longitudinally apart on the base plate a sufficient distance to receive suitable indicia carrying slides 15, which are constructed as will be presently more fully described. 100 The edges of the slit portions of the plate 1 are bent outward at an oblique angle as shown at 12 and provide guides for the flanges 16 arranged longitudinally along

the side edges of the slides 15 so that these slides will be guided by said lips or flanges 12 and held in operative relation to the base plate.

5 The base plate 1 is divided into three fields or portions 20, 21 and 22 which are preferably of the same length and the central portion or field 21 is designed to receive the slides 15 consecutively, the slides 10 from the field 20 alternating with those from the field 22.

The central field 21 has arranged above it on the base plate 1 suitable indicia to call attention to the slides contained in 15 this field, and preferably the word "We need" are placed conspicuously above this field. It will then be obvious that when the slides bearing the names of articles needed are moved into the spaces in the field 21, 20 that attention will be immediately attracted to them by glancing at the indicator and show just what articles are desired to be purchased, if the device is used as a household reminder; or obviously, the slides may 25 contain thereon dates, or names of persons, or anything to which attention is to be attracted.

The slides 15 are each provided with an indicia carrying body portion 17 having the 30 flanges 16 extending longitudinally along the side edges thereof and adapted to slidably engage under the flanges 12 of the base plate, as shown in Fig. 2 while from one end of the slide extends upwardly a lug 18 35 to form a finger grip for manipulating the slides to move them back and forth. A stop 18^a for limiting the movement of the slides inwardly of the plate 1 is formed at the inner end of each slot so that when the slide 40 reaches the inner end of its guide 10, it will be stopped from sliding beyond said guide.

It will thus be seen that when any household article gives out and attention of the householder is desired to be called thereto, 45 the attendant, or anyone else, moves the slide at one side of the plate 1 into the central position for instance, should matches be needed, the slide bearing the word "Matches" 50 is moved, as shown in Fig. 1 and arranged directly within the field 21 below the phrase "We need", so that a glance at the indicator will show exactly the articles which are to be supplied.

This arrangement of the slides at opposite sides of the board so that when moved 55 inwardly to the central field they will alternate, provides for a balanced board capable of carrying a maximum number of slides.

It is, of course, understood that the board 60 may be finished in any desired manner to render it attractive, or sanitary.

In the form shown in Figs. 5^a to 8, the arrangement in principle is the same, the only difference being that the base plate 1^a 65 is composed of metal, preferably enamelled,

and the slots 10^a instead of having the deflected flanges along the edges thereof, as shown in the other figures, have their edges in the same plane as the body portion of the plate, as is shown clearly in Fig. 6, and these 70 slots are made of sufficient size to receive guide lugs or fingers 16^a carried by the slides 15^a.

The slides 15^a are all constructed exactly alike, and hence one only will be described 75 in detail. Each of these slides comprises a plate or body portion 23 having at their opposite ends down-turned lugs 24 and 25, said lugs being notched at their opposite side edges, as shown at 26. These notches 26 80 are designed to receive the side walls of the slots 10^a when the slides are operatively placed on the base board 1^a. A finger grip 27 extends laterally outward from one end of the slide and is designed to facilitate the 85 manipulation of the slides in the same manner as that described in relation to the other figures.

The binding strips or frame members 2^a are removable to permit the slides 15^a to be 90 inserted or removed when desired, and others substituted, thereby adapting the indicator to be used for advertising and similar purposes.

From the above, it will be readily seen 95 that the gist of the invention resides in providing a device of this character by means of which the attention attracting slide may be seen at a glance, and while the two forms herein illustrated and described accomplish 100 the object, it is to be understood that various constructions may be employed for this purpose.

Without further description it is thought 105 that the features and advantages of the invention will be readily apparent to those skilled in the art, and it will of course be understood that changes in the form, proportion and minor details of construction may be resorted to, without departing from 110 the spirit and scope of the claimed invention.

I claim:

1. A device of the class described comprising a base having a plurality of guides, said guides extending alternately in opposite directions and having a portion thereof arranged parallel and one above the other, indicia carrying slides mounted to travel in said guides, and means for manipulating 115 said slides.

2. A device of the class described comprising a base plate having a central and two side fields, guides mounted in said side fields with their inner ends overlapping in the center field, said overlapping inner ends being arranged one above the other with those extending into one side field alternating with those extending into the other, and indicia carrying slides mounted to travel in said guides and be disposed within said cen- 120 125 130

ter field whereby the slides may be conspicuously displayed to adapt their indicia to be seen at a glance.

3. A device of the class described comprising a base plate having a plurality of longitudinally extending parallel fields, slots extending transversely of said fields, the inner ends of the slots of one side field overlying the inner ends of those of the other

side field, and positioned in the center field, 10 and indicia carrying slides adapted to travel in said slots and equipped with means for manipulating them and for stopping them in adjusted position.

Signed at Altoona, in the county of Blair 15 and State of Penna. this fourth day of January, A. D. 1928.

JOSEPH DE BRACHT.
